UNITED STATES PATENT OFFICE.

PER AUGUST ANDERSON, OF NEW YORK, N. Y.

FAN.

1,276,703.

Specification of Letters Patent. Patented Aug. 27, 1918.

Application filed July 31, 1917. Serial No. 183,681.

To all whom it may concern:

Be it known that I, PER AUGUST ANDERSON, a citizen of the United States, and resident of the borough of Manhattan, city, county, and State of New York, have invented a certain new and useful Improvement in Fans, of which the following is a specification.

My invention relates to power driven fans and more particularly to that type thereof in which the fan member or element oscillates about a pivot relatively to the remainder of the construction instead of rotating. The principal object of my invention is to provide a construction in which the fan is suspended, for instance from the ceiling, and in which said fan is adjustable to swing in different planes.

My invention further contemplates a construction in which the operation is substantially noiseless and in which the oscillation of the fan member is constant and even and in which vibration and irregular movement is avoided. Other objects of my improvement will appear from the description hereinafter and the features of novelty will be pointed out in the appended claims.

In the accompanying drawings, which for illustrative and descriptive purposes show an example of my improvement, Figure 1 is a vertical section of my improved construction; Fig. 2 is an elevation looking at right angles to Fig. 1; Fig. 3 is an enlarged detail section of the driving mechanism and its casing; Fig. 4 is a detail elevation of the same, partly broken away; Fig. 5 is a detail section on the line 5—5 of Fig. 3 and Fig. 6 is a detail plan view of a supporting frame forming part of my improved construction.

As shown in the illustrated example, my improvement comprises a preferably cylindrical casing 10 of suitable material and closed at one end by means of a preferably removable cover 11 detachably secured in position for instance by means of screws or the like 12, and preferably provided with a manipulating knob 11^a. At its opposite end the casing 10 is provided with a plurality of preferably integral arms 13 which extend outwardly from said casing in an axial direction and converge toward each other, the outer ends of said arms being connected together by spaced and parallel cross-pieces 14. This construction provides a tapering spider which projects from one end of said casing 10 in axial registry therewith; in the

normal, operative condition of the parts this spider is covered by a tapering shell 15 which fits over the arms 13 and is detachably secured in position in any suitable manner as by means of screws 16. It will be seen that the casing 10, cover 11 and shell 15 when combined, form a complete casing, the one end of which is closed and the other tapering end of which is open as shown in Figs. 1, 3 and 4. The arrangement further includes a member 17 internally screw-threaded to receive the screw-threaded stem 18 of a head 19 to which the fan member 20 of any suitable or well known construction is secured in any convenient manner. The member 17 forms part of a disk 21 rotatably mounted between the cross-pieces 14 at the open end of the shell 15 as shown in Figs. 3 and 4. In the illustrated example the disk 21 is operatively combined with a sprocket member or wheel 22 so as to rotate therewith, said sprocket member or wheel accommodating a sprocket chain 23, the opposite ends of which are connected by means of coil springs 24, with links 25. The latter are in turn pivotally connected with cranks 26 located at opposite ends of a shaft 27 in off-set relation to each other, said shaft 27 being journaled in a housing 28. The shaft 27 carries a worm wheel 29, which meshes with a worm gear 30, the worm wheel and worm gear being both located within the housing 28 as shown in Fig. 3. The worm gear 30 is carried by a shaft 31 one end of which is journaled in a cap 32 detachably combined with the housing 28 and the other end of which is rotatably mounted in and extends through said housing 28 as shown in Fig. 3. The projecting end of the shaft 31 carries a wheel 33 which is provided, preferably at diametrically opposite points, with pins or lugs 34 extending outward substantially perpendicular to the face of the wheel 33. The wheel 33 is preferably formed with a rather heavy rim so as to act in the nature of a fly-wheel or balance wheel when the fan is in operation. The lugs 34 project through openings 35 formed in an opposed disk 36 which is preferably constructed of leather or similar material mounted upon a carrier 36^a, said disk 36 and carrier 36^a being carried by the power or driving shaft 37 of an electric motor 38. The latter is connected by means of wires 39 which pass through an axial opening 11^b of the knob 11^a, with a coupling

member 40 arranged to be detachably connected with a coöperating coupling member 41 connected by means of wires 42 with a source of electricity. The housing 28 and 5 its coöperating parts and the motor 38 with its coöperating parts are both secured upon a platform 43 located within the casing and supported upon lugs 44. The latter are provided with screw-threaded recesses for the 10 reception of screws 45 which pass respectively through the casing 10 and through an arm 13 and whereby the platform 43 and with it the housing 28 and motor 38 are rigidly and securely fastened in operative position 15 within the casing as a single unit.

In order to suspend the fan from the ceiling or other support, the casing 10 is provided with a pair of annular ribs 46, between which a split collar 47 fits, as shown in Figs. 20 1 and 2, said collar being provided with lugs 48 having screw-threaded apertures for the accommodation of a thumb screw 49 whereby the collar 47 is spread and contracted. The collar 47 is formed with two 25 upright, integral members 50 terminating in a sleeve 51 which in the illustrated example fits upon the end of a tube 52 and is secured thereon for instance by means of a screw 53. The tube 52 is slidably mounted or telescopes 30 within a second tube 54, the upper end of which is secured to a carrying member 55 for instance by means of a screw 56, said carrying member 55 being fastened to the ceiling or other support 57 in any suitable 35 manner as by means of screws 58. A packing 59 is provided at the outer end of the tube 54 in engagement with the tube 52 and is held in operative position by means of a suitably shaped cap 60 which is in screw- 40 threaded engagement with said tube 54 as shown in Fig. 1. A similar packing 61 is located at the inner end of the tube 52 in engagement with the inner surface of the tube 54 and is secured in position by means of a 45 preferably tubular cap 62 which screws into the inner end of said tube 52 as shown in Fig. 1. These packings 59 and 61 are adjusted so as to provide the desired frictional engagement between the telescopic tubes 52 50 and 54 and to prevent the inner tube 52 from unintentionally sliding downward relatively to the outer tubes 54. It will be seen that the position or height of the fan may be readily adjusted within the limits of 55 the construction by simply sliding the tube 52 into or out of the tube 54. In the preferred construction a coil spring 63 is provided for assisting the raising of the fan and for preventing a complete separation of 60 the tubes 52 and 54. As shown in Fig. 1 the coil spring 63 is located within the tube 54 and has its one end connected with a cross-bar 64 carried by the cap 62 and its other end connected with a cross-bar 65 located within 65 the carrying member 55. I further prefer to

provide means whereby rotation of the tube 52 about its axis relatively to the tube 54 is prevented, without interfering with the desired sliding movement of said tube 52. In the drawings this means comprises a screw 70 66 which extends inwardly through the outer tube 54 into a slot 67 extending lengthwise of the inner tube 52. It will be seen that, in addition to maintaining the tube 52 against rotation in the tube 54, this arrangement 75 also prevents complete withdrawal of the tube 52 from the tube 54. In practice the wires 42 may be run through the tubes 52 and 54 to the source of electrical power as indicated in Fig. 1. 80

In operation the motor 38 is electrically driven and drives the shaft 37 which in turn rotates the disk 36 and its carrier 36^a; the rotative motion of the disk 36 is communicated to the disk 33 through the medium of 85 the pins or lugs 34 and thus brings about an actuation of the shaft 31 and worm gear 30. Owing to the fact that the disk 36 is made of leather or the like this transmission of motion from the motor 38 to the shaft 31 90 and worm gear 30 is absolutely noiseless and without vibration. The wheel 33 acting as a fly-wheel or balance-wheel also helps to steady the rotary motion of the parts and to render the transmission substantially constant and free from jerks. The actuation of 95 the worm gear 30 in turn causes a rotation of the worm wheel 29 and shaft 27 whereby the cranks 26 are operated in a circle as will be readily apparent from the drawings. As 100 the cranks 26 are thus actuated a pulling force will be alternately exerted on each link 25, which force will be resiliently transmitted to the sprocket chain 23 by the springs 24 and through the medium of the sprocket 105 22 will oscillate member 17 and fan member 20 in a manner corresponding substantially to a manual operation of any usual hand fan.

The addition of the springs 24 in the connections between the driving mechanism and the fan member renders the oscillation of the fan member 20 absolutely even and noiseless and at the same time by providing the necessary flexibility, permits the mechanism to pass the dead centers without bringing about any sudden breaks in the movements of the fan member. The oscillation of the latter is thus absolutely smooth and free from any jerkiness. In addition to 110 this said springs will permit the fan member to yield relatively to the driving mechanism if said fan member in its oscillations should encounter an obstacle of any kind. Similarly if a person should come into accidental 115 contact with said fan member it will give or yield, without injury to the person or to itself or its coöperating mechanism. 120

The fan member 20 may be caused to oscillate in any desired vertical plane by 130

simply first loosening the screw 49 to release the pressure of the collar 47 upon the casing 10 and then rotating said casing in said collar until the fan member reaches the desired position. The thumb screw 49 is then again tightened up to again cause the collar 47 to securely grip the casing 10 which as a result is clamped in the adjusted position. The motor 38, housing 28, and their 10 connected and coöperating parts all partake of the adjusting movement of the casing 10 and fan member 20.

In any position the fan member 20 is oscillated to produce a gentle disturbance of 15 the air whereby an air current is created which is cooling and beneficial and in no case constitutes a draft. The apparatus may be conveniently adjusted to the proper height by simply sliding the inner tube 52 20 into and out of the outer tube 54; it will be understood that the apparatus is held in its adjusted position by friction assisted by the action of the spring 63.

My improved fan construction is extremely simple in construction and efficient 25 in operation and at the same time presents a highly ornamental appearance at all times; the apparatus may be easily and quickly suspended from any desired support.

30 All parts of the structure are readily accessible for cleaning and other purposes and may be readily disassembled if this should be desired for any reason. When the need for the fan has temporarily passed the tube 35 52 carrying the casing, the motor, the fan member and coöperating parts may be completely disconnected from the tube 54 and stored away, ready to be operatively re-assembled when desired. This makes it unnecessary to disturb the outer tube and its carrier unless it should be desired.

The subject matter of the present case is of the same general class as that contained in my Patent, No. 1,261,753 of April 9, 1918.

45 Various changes in the specific form shown and described may be made within the scope of the claims without departing from the spirit of my invention.

I claim:

50 1. The combination of a depending support, a member extensibly connected with

said support, a supporting device fixed upon and depending from said member, a casing carried by said supporting device and rotatable relatively thereto about an axis extending in the same direction as that of the depending support, actuating mechanism within said casing and a fan member carried by said casing and actuated by said mechanism. 55 60

2. The combination of a depending extensible supporting device, a forked member detachably fixed upon the same, a collar carried by said forked member and located in a plane transverse to said device, a casing 65 rotatably mounted in said collar and having an axis of rotation common to the axis of the collar, actuating mechanism in said casing and a pivoted fan member carried by said casing and actuated by said mechanism. 70

3. The combination of supporting means, a fan member pivotally connected with said means, actuating mechanism carried by said means, and a pair of resilient connections between said actuating mechanism and said 75 fan member operating in opposition to each other whereby said fan member is oscillated on its pivot, first in one direction and then in the opposite direction.

4. The combination of a casing, driving 80 mechanism within said casing, a driven shaft operatively connected with said mechanism, off-set cranks carried by said shaft, a fan member pivotally connected with said casing and resilient connections between said 85 cranks and said fan whereby the latter is oscillated on its pivot.

5. The combination of a casing, driving mechanism within said casing, a driven shaft operatively connected with said mechanism, 90 off-set cranks carried by said shaft, a fan member pivotally connected with said casing, a sprocket member connected with said fan member, a sprocket chain operatively combined with said sprocket member, links 95 pivotally connected with said cranks and coil-springs connecting said links with said sprocket chain.

In testimony whereof, I have hereunto set my hand.

PER AUGUST ANDERSON.
